UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,181,675.

Specification of Letters Patent.

Patented May 2, 1916

Application filed January 2, 1913. Serial No. 739,658.

To all whom it may concern:

Be it known that I, ALFRED G. F. KUROWSKI, a citizen of the United States, residing in Brooklyn, in the county of Kings, city and State of New York, have invented certain new and useful Improvements in Type-Writing Machines, of which the following is a specification.

This invention relates to typewriting machines of the class in which the type-bars strike against a visible part of the platen, usually the front thereof.

One of the main objects of the invention is to produce a machine of this class, which is simple, compact, inexpensive and easily operable.

One of the features of my invention is the provision of a reduced number of key levers for a full set of letters and other characters.

The invention comprises a machine in which the type-bars are each provided with four characters, and mechanism is provided for shifting the platen and type-bar segment into four different operating positions.

I have devised a machine in which the type-bar segment and the platen roller may be shifted simultaneously but in opposite directions. The segment in which the type-bars are pivoted, is movable up and down, the means for guiding the segment during such movements being substantially like that disclosed in Patent No. 1,144,766, dated June 29, 1915. The segment is lifted and lowered by means of a rock-shaft extending across the machine and having a forwardly projecting arm connected to the segment frame. A rearwardly extending arm secured to said rock-shaft is connected through a link to the shift rail frame which supports the platen, so that when the rock-shaft is rotated, the segment and the platen are caused to move in opposite directions. Said rock-shaft is actuated by means of shift keys, which operate rocking members provided with arms co-operating with a cam disk on said rock-shaft.

The invention also involves a novel form of type-action in which the key levers are connected through links to bell cranks pivoted in a slotted support, the bell cranks being connected through substantially hori-

zontal links to the type-bars, and the arrangement being such that the vertical movement of the type-bar segment, carrying with it the type-bars, does not affect the position of the key levers or modify the type-bar action. The said bell cranks may be pivoted by means of bosses formed thereon to provide fulcrums, the slots in which the bell cranks are mounted being provided with recesses to receive and form bearing surfaces for said bosses. A slotted retaining plate overlies said recesses to prevent displacement of the bell cranks.

Other features and advantages will hereinafter appear.

In the accompanying drawings, which illustrate a typewriting machine constructed in accordance with the principles of my invention, Figure 1 is a perspective view showing a shiftable type-bar segment and platen, shift keys and associated mechanism for shifting the segment and platen, a type-bar and operating means therefor. Fig. 2 is a sectional elevation showing the parts in their normal position of rest. Figs. 3, 4 and 5 are similar views showing a type-bar in striking position, and the type-bar segment and platen shifted by the capital, character, and figure-shift keys respectively. Fig. 6 is a top plan view showing the keyboard, the type-bar segment and the shift rail, and their connections with the shift keys. Figs. 7 and 8 are respectively a sectional elevation and a plan view showing a bearing block for the platen axle. Figs. 9 and 10 are respectively a plan and an elevation of the universal frame. Figs. 11, 12 and 13 are detail views illustrating a bell crank lever and its bearings. Fig. 14 is a front elevation view of the machine.

The key-board, as shown in Fig. 6, comprises a set of twenty-six type-keys 1, each operatively connected to a corresponding type-bar 2 provided with four types *a*, *b*, *c*, *d*. The types *a* and *b* are respectively a capital and a lower case letter, the type *c*, a figure or punctuation mark, as indicated above the letter on the corresponding key, and the type *d*, a fraction or other character, as indicated below the letter on the corresponding finger key. The key-levers 4 extend rearwardly and are fulcrumed on a

universal fulcrum rod 5, which extends across the machine, and is secured at its ends in the frame 6 of the machine.

Above the key-levers 4 and extending transversely of the machine is a curved supporting bar 7 provided with vertical parallel kerfs or slots 8, in which are pivotally supported bell crank levers 9 connected through links 10 to the key levers. By reference to Figs. 11, 12 and 13, it will be seen that the bell cranks 9 are provided with spherical bearings 11, which are received in cylindrical openings 12, formed by recesses in the slots 8. A slotted retaining plate 13 is removably fitted over the bar 7 to secure the bell crank levers in position. The type-bars 2 are pivoted on the curved pivot rod 14, supported in the type-bar segment 15, which is formed with radially disposed slots 16 to receive the type-bars. Links 17 connect the type-bars with the bell crank levers 9. It will be observed that the type-bar and the operating mechanism therefor are so related, that the vertical movement of the type-bar segment to raised or lowered position will simply swing the link 17 about its connection with the bell crank as a fulcrum. The position of the key levers therefore remains unchanged during the shifting of the segment, and the type bar action is also unaffected by a change in the position of the segment. The type-bar segment 15 is formed with forwardly extending arms 18, to which is attached a basket 19, provided with a pad 20 forming a support for the type-bars. The type-bar segment is supported and guided in its vertical movement by the legs 21 guided between vertical members 22 of the machine frame. The parts 21 and 22 are formed with recesses 23 to receive anti-friction guide rollers 24 which prevent any movement of the segment frame except in a vertical direction. The construction of this frame and the means for supporting and guiding it in its shifting movement are set forth in my patent above referred to, and need not further be described here.

The key-board, in addition to the twenty-six keys above referred to, may additionally comprise a set of decimal tabulator keys 25, ten of such keys being shown in Fig. 6. As the tabulating mechanism does not form a part of the present invention, it has not been illustrated in the drawings.

Capital shift keys A and A', a figure shift key C, and a character shift key D are provided for shifting the segment frame and the platen. A back-spacer key and a margin release key may also be employed, but illustration thereof has been omitted as being unnecessary to an understanding of the present invention. The shift keys A, A', C, and D are carried respectively by levers 26, 27, 28 and 29, each fulcrumed on the rod 5. The mechanism for lifting the type-bar seg-

ment simultaneously with the lowering of the platen and vice-versa, comprises a rock shaft 30 extending across the machine and journaled at its ends in the frame, and a cam disk 31 fixed to the rock shaft. Rock arms 32 are also secured to said shaft and extend forward into slots 33 formed in the legs 21 of the segment frame. The arms 32 are slotted to receive pins 34 carried by the legs 21. This construction provides a positive operating connection between the rock 70 and the segment, so that the latter is moved up or down in a vertical direction while said shaft is rocked.

The platen 35 is supported by a shift rail 36 connected at its ends to rock arms 37 extending forward from a supporting bar 38. The platen frame 39 carries a rod 40 to which is secured a bracket 41. A guide roller 42 carried by the bracket 41 runs on the shift rail 36, the bracket 41 extending beneath said rail to prevent the platen from being lifted independently of the rail. Crank arms 43 extending rearwardly from the rock shaft 30 are connected through links 44 to the arms 37. The operating mechanism between the capital shift key levers and the rock shaft 30 comprises a rock shaft 45 carrying rock arms 46 and 47 having projections in the path of the shift key 95 levers 26 and 27 respectively. Integral with the arm 46 is an upwardly extending arm 48, adapted to engage in a notch 49 formed in the disk 31. When either of the capital shift keys is depressed, the shaft 45 is rocked 100 and carries the arm 48 rearwardly to the position shown in Fig. 3, thereby rocking the shaft 30 in a direction to lower the type bar segment and lift the platen. The relative position of the segment and the platen 105 is now such that when the type keys are operated, the upper case types *a* are brought up to the platen. When the capital shift key is released, the type-bar segment and the platen are restored to initial position by 110 means of a roller 50 bearing on the cam surface 51 of the disk 31. The roller 50 is carried by a rock arm 52 mounted on a stationary pivot 53 and operated by a spring 54.

When the shift key D is depressed, the 115 rock shaft 30 is rotated in the opposite direction by means of an arm 55 which engages a notch 56 in the cam disk 31 and rotates the latter to the position shown in Fig. 4. The arm 55 is secured to a rock 120 shaft 57 which carries an arm 58 beneath the shift key lever 29 and in position to be operated thereby. When the shift key D is depressed, the rock shaft is rotated in a direction to swing the arms 32 upward, and the arms 43 downward so that the type-bar 125 segment and platen are brought to their highest and lowest position respectively.

The lever 28 of the figure shift key C is connected through a link 58' to a lever 59 130

- having a pivotal connection 60 with a bracket 61 secured to the frame of the machine. The forward end of the lever 59 is adapted to engage in a notch 62 of the disk 31, and rotates the latter to the intermediate position shown in Fig. 5, so that the type-bars, when operated carry the type *c* up to the platen. A tail 63 of the lever 59 engages beneath the bracket 61 and limits the movement of the lever. When the disk 31 is operated either to the position shown in Fig. 5 or that of Fig. 4, the roller 50 rides up the incline 64, and when the shift key is released, pressure of the roller on said incline returns the disk and the parts operated thereby to initial position. The rotation of the disk in both directions is limited by a depending arm 65 secured to the shaft 30, and extending between the rock shafts 45 and 57.
- 20 The platen is vertically movable in the carriage frame 66, being supported and guided by bearing blocks 67, in which the axle 68 of the platen is journaled. The blocks 67 move in guides 69 of the carriage frame, anti-friction bearing rollers or balls 70 supported in a cage 71, being interposed between the bearing block and the frame. The blocks 67 are provided with flanges 72 projecting beyond the edges of the guides 69. The platen is supported by rock arms 73 fixed to a rock shaft 74 and having bifurcated ends 75 to straddle the platen axle 68.
- The universal frame F, (Figs. 9 and 10) consists of two relatively movable members 76 and 77. The member 77 is formed with a vertical section 78 provided with slots 79 through which extend shouldered screws 80 threaded into the member 76, thereby permitting a relative vertical movement of the two members. The member 76 has an arc-shaped flange 81 located behind the type-bars in position to be engaged by each type-bar as the latter is operated and thereby move the frame F. The frame is guided in its horizontal movement by pins 82 fixed to the segment 15 and extending through sleeves 83 secured to the member 76. The member 77 is supported and guided in its horizontal movement by a supporting bar 84 (Fig. 2) secured to a stud 85 on the frame of the machine. The upper end of the bar 84 extends horizontally and carries a shouldered screw 86 which extends through a slot 87 formed in the member 77 and permits the latter to slide on its support 84. The frame F is connected through levers 88 to the escapement mechanism which may be of the usual construction employed in the Underwood machine. The construction of the frame F, as above described, permits the member 76, attached to the segment frame, to move up and down therewith when the shift keys are operated, without changing the position of the member 77, and permits the same operation of the escapement mech-
- anism for any position of the segment. The frame F is returned after each operation by a spring 90 connected at one end to a stationary arm 91 and at its opposite end to a pin 92 on the frame F.
- Variations may be resorted to within the scope of the invention, and portions of the improvements may be used without others.
- Having thus described my invention, I claim:
1. In a typewriting machine, the combination of a type-bar segment, type-bars, means for operating the type-bars, a platen, and means to simultaneously shift the type-bar segment and platen, each in opposite directions from its normal position of rest. 75
  2. In a typewriting machine, the combination of a type-bar segment, a platen, and means to simultaneously shift the segment and platen vertically, each in opposite directions from its normal position of rest. 80
  3. In a typewriting machine, the combination of a type-bar segment, a platen, a shift key operable to simultaneously shift said parts in opposite directions from one case 90 position in which said parts are normally at rest, to a second case position, and a second shift key operable to shift said parts from said first-named position in the reverse direction from that effected by said first-named key to a third case position. 95
  4. In a typewriting machine, the combination of a type-bar segment, a platen, mechanism to move each of said parts vertically in either direction, a key to actuate said 100 mechanism, and simultaneously move said parts in opposite directions from a normal position of rest, and a separate key to actuate said mechanism and move said parts from said normal position in the reverse directions from those effected by the first-mentioned key. 105
  5. In a typewriting machine, the combination of a roller platen, a type-bar segment, mechanism for lifting and lowering the 110 platen above and below its normal position of rest, and inter-connected mechanism to lower the segment when the platen is lifted, and vice versa, said mechanisms forming means to positively determine the relative 115 position of the platen and segment and prevent up or down movement of either the platen or segment independently of the other. 120
  6. In a typewriting machine, the combination of a set of type-bars, a support therefor, a platen, shift keys, mechanism operated by the shift keys to shift the platen in either direction from its normal position of rest, means to move the said support in the reverse direction when the platen is shifted, types on each type-bar comprising a type to strike the platen at the printing point when the platen is in said normal position of rest, types to strike the platen at the print- 125 130

ing point while the platen and said support are in their shifted positions, and stops to determine the shifted positions of the platen and said support.

5 7. In a typewriting machine, the combination of a platen, type-bars, a support for the type-bars, a shift key, operating mechanism for moving the platen and said frame in opposite directions when the shift key is operated, and a second shift key operable to move the platen and frame in the directions reverse to those effected by the first key.

8. In a typewriting machine, the combination of a platen, means to shift the platen in 15 opposite directions from its normal operative position to operative shifted positions, type-bars, a frame carrying said bars, and means to shift said frame simultaneously with the platen but in a reverse direction, each of said type-bars comprising types, one positioned to strike the platen at the printing point when the platen is in said normal position, and the others positioned respectively to strike the platen at 20 the printing point when the platen is in said shifted positions.

9. In a typewriting machine, the combination of a platen, shift keys, mechanism between said keys and the platen for lifting the platen when one key is operated and for 30 lowering the platen when another key is operated, type-bars, a frame in which said type-bars are pivoted, and mechanism to lower and lift said frame respectively when 35 the platen is lifted and lowered.

10. In a typewriting machine, the combination of a platen, type-bars, four printing characters carried by each type-bar, and mechanism for moving and supporting the 40 platen in four different positions corresponding to said characters, said mechanism comprising keys operable to bring the platen to three of said positions, and means to automatically return the platen to the fourth 45 position when the operated key is released.

11. In a typewriting machine, the combination of a platen, independently operable shift keys, mechanism operated by said keys independently to shift the platen different 50 distances from normal position in the same direction and also in the opposite direction from normal position, each of said keys being supported and maintained in its normal position of rest during the operation of 55 the other keys, type-bars, type carried thereby in positions corresponding to the positions of the platen, and means to operate the type-bars.

12. In a typewriting machine, the combination of a platen, a shift key, mechanism associated therewith to shift the platen in one direction, and a plurality of additional shift keys operable to shift the platen different distances in the reverse direction.

65 13. In a typewriting machine, the com-

bination of a platen, shift keys and associated mechanism operable to shift the platen in opposite directions from a normal position of rest, a type-bar segment, means to move the segment simultaneously with the 70 platen but in the reverse direction, and means to automatically return the segment and platen to normal position when the shift keys are released.

14. In a typewriting machine, the combination of type-bars, four different characters carried by each type-bar, a platen having four rest positions corresponding to the four characters of a type-bar, means for selectively shifting the platen to each of said 80 positions and stopping it in the selected position, a supporting frame in which said type-bars are pivoted, and means to shift said frame simultaneously with the shifting of the platen.

15. In a typewriting machine, the combination of a platen, type-bars, a frame supporting said type-bars, vertical guides for said frame and platen, a rock-shaft, rock arms carried thereby, connections between 90 the rock arms and said frame and platen, a key for rocking the rock shaft in one direction from its normal position of rest, and thereby shifting the platen and said frame vertically in opposite directions, and a key 95 for rocking said shaft in the reverse direction from said position of rest and thereby shift the platen and said frame in the opposite directions from those in which they are shifted by the first-mentioned key.

16. In a typewriting machine, the combination of a platen, a type-bar segment, a rock shaft, means to rock said shaft in either direction from a normal position of rest, means to automatically return said shaft to 105 said normal position, rock arms extending in opposite directions from the rock shaft, connections between said arms, the platen and said segment, and guiding means to effect a straight line parallel movement of the 110 platen and segment when the said shaft is rocked.

17. In a typewriting machine, the combination of a platen, a supporting frame therefor, a segment frame, type-bars supported thereby, a rock shaft, a rock arm secured thereto and operatively connected to the segment frame, a second rock arm secured to said shaft, means connecting said second arm to said supporting frame, shift 115 keys, operating connections between the shift keys and said rock shaft, for rocking the shaft in either direction from its normal position of rest, and means to guide the segment frame and platen in vertical 120 straight lines when the shaft is rocked.

18. In a typewriting machine, the combination of a platen, a shift rail supporting the platen, a segment frame, type-bars pivoted in and supported by the seg-

- ment frame, a rock shaft, a forwardly extending arm secured to the rock shaft and connected at its forward end to the segment frame, a second arm secured to the rock shaft, and extending rearwardly, connections between said second arm and the shift rail, shift keys, means operated by one shift key to rock said shaft in one direction from a normal position of rest and effect a relative shifting of the platen and segment frame to one shift position, and means operated by the other shift key to rock said shaft in the reverse direction from said normal position and thereby effect a relative shifting of the platen and segment to a different shift position.
19. In a typewriting machine, the combination of a platen, a type-bar segment frame, a rock shaft, shift keys, mechanism between said keys and the rock shaft for rotating the latter in opposite directions from a normal position of rest, means to return the rock shaft to its initial position when the shift keys are released, and connections between the rock shaft, the platen, and the segment frame.
20. In a typewriting machine, the combination of a platen, a frame supporting the platen, a rock shaft, a shift key, means operated thereby to rock the shaft, a cam carried by said shaft, means to operate said cam and cause the cam to return the shaft when the shift key is released, and a connection between the rock shaft and said supporting frame for lifting and lowering said frame when the shaft is rocked.
21. In a typewriting machine, the combination of a platen, a type-bar segment frame, a rock shaft rotatable in either direction from an initial position of rest, shift keys for operating the rock shaft, a cam secured to said shaft, a device co-operating with said cam to automatically restore the rock shaft to initial position when the shift keys are released, and connections between the rock shaft, the segment frame and the platen, for shifting said frame and platen when the rock shaft is rocked.
22. In a typewriting machine, the combination of a platen, a type-bar segment, type-bars pivotally supported therein and extending forward in a substantially horizontal direction, a support for the forward ends of the type-bars, bell-cranks, a stationary support therefor, links connected to the type-bars and extending forward to the bell-cranks for pivotal engagement therewith, key-levers operatively connected to the bell-cranks and imparting forward and rearward movement to the bell-cranks at their points of pivotal engagement with the links, means for lifting and lowering the type-bar segment to positions above and below its normal position of rest, and means for lowering and lifting the platen to positions below and above its normal position of rest, the said movements of the segment and platen being simultaneous in opposite directions, said links arranged to swing about their points of connection with the bell-cranks during the lifting and lowering of the type-bar segment while the bell-cranks remain at rest.
23. In a typewriting machine, the combination of type-bars; a supporting frame therefor; means for lifting and lowering said frame and type-bars; and a universal frame comprising mechanically-connected members relatively movable in a vertical direction, one of said universal frame members being supported on the first-named frame so as to be lifted and lowered therewith, and being disposed in position to be operated by the type-bars, said universal frame moving as a unit without relative movement of its said component members when operated by the type-bars.
24. In a typewriting machine, the combination of a type-bar segment; type-bars carried thereby; means for lifting and lowering said segment and type-bars; and a universal frame comprising two members mechanically connected together for movement relatively to each other in a vertical direction, one of said members being connected to said segment so as to be lifted and lowered therewith while the other member remains stationary, and being located in position to be operated by said type-bars, said universal frame moving as a unit without relative movement of its said component members when operated by the type-bars.
25. In a typewriting machine, the combination of a type-bar segment, type-bars carried thereby, means for lifting and lowering said segment, a universal frame comprising a member supported by the segment and movable in a horizontal direction, and a second member slidably connected to said first named member for vertical movement relative thereto, permitting said second member to remain at rest while the first-named member moves up and down with said segment, said sliding connection preventing relative movement of said members in a horizontal direction.
26. In a typewriting machine, the combination of a type-bar segment, type-bars carried thereby, means for lifting and lowering the segment, a universal frame bodily movable in a horizontal direction, said frame comprising a member supported by the segment and movable with the segment when the latter is lifted and lowered, and a rearwardly extending member having a sliding connection with said first named member, and means to support said second named member in a horizontal position and hold it against vertical movement, said sliding connection preventing relative move- 136

- ment of said frame members in a horizontal direction.
27. In a front-strike typewriting machine, the combination with a revoluble platen, of a type-bar support, type-bars mounted thereon to swing upwardly and rearwardly to the front face of the platen, keys to actuate the type-bars, shift keys operable to shift said support through different distances in the same direction from a normal position of rest to different case positions, said type-bars comprising types to strike the platen at the printing line when the said support is in its normal position of rest, types for each of said case positions to strike the platen at the printing line when the said support is shifted by said shift keys, and a shift key operable to shift said type-bar support in the opposite direction from its normal position of rest, said type-bars having types thereon to strike the platen at the printing point when the support is in said last-mentioned shifted position.
28. In a typewriting machine, the combination of a platen, a type-bar support, type-bars mounted thereon, a shift key, mechanism controlled thereby to shift said support in one direction from a normal position of rest, a plurality of additional shift keys operable to shift the said support different distances in the reverse direction to different case positions, and types carried by the type-bars in positions corresponding to each of said positions of the said support.
29. In a typewriting machine, the combination with a platen, of a type-bar support, type-bars mounted thereon to swing to printing position at the platen, shift keys, means operated thereby to shift the platen and type-bar support in opposite directions from a normal position of rest when either shift key is operated, the directions in which the platen and said support are shifted when one shift key is operated being the reverse to the directions in which they are shifted when the other shift key is operated, stops to limit the shifting movements of the platen and type-bar support by said keys, and thereby determine the shifted positions of the platen and said support, and means to automatically restore the parts to their normal positions of rest when the shift keys are released.
30. In a typewriting machine, the combination with a platen, of a type-bar support, type-bars mounted thereon to swing to printing position at the platen, shift keys, means operated thereby to shift the platen and type-bar support in opposite directions from a normal position of rest when either shift key is operated, the directions in which the platen and said support are shifted when one shift key is operated being the reverse to the directions in which they are shifted when the other shift key is operated, stops to limit the shifting movements of the platen and type-bar support by said keys, and thereby determine the shifted positions of the platen and said support, means to automatically restore the parts to their normal positions of rest when the shift keys are released, when the other shift key is operated, stops to limit the shifting movements of the platen and type-bar support by said keys and thereby determine the shifted positions of the platen and said support, means to automatically restore the parts to their normal positions of rest when the shift keys are released, an additional shift key operable to effect a relative shifting of the platen and said support from their normal positions of rest to a different position from that determined by said stops, and a stop coöoperating with said additional shift key to determine said last-mentioned position.
31. In a typewriting machine, the combination with a platen and a type-bar support, of type-bars mounted on said support to swing to printing position at the platen, means forming a connector between the platen and said support for causing them to shift in opposite directions when either the platen or said support is shifted in either direction from its normal position of rest, a shift key for operating said connector to shift the platen and said support each to one limit of its movement, a second shift key to move the platen and said support each to the opposite limit of its movement, stops to determine said limits, and means to restore the platen and said support to their normal positions of rest when the shift keys are released.
32. In a typewriting machine, the combination with a platen and a type-bar support, of type-bars mounted on said support to swing to printing position at the platen, means forming a connector between the platen and said support for causing them to shift in opposite directions when either the platen or said support is shifted in either direction from its normal position of rest, a shift key for operating said connector to shift the platen and said support each to one limit of its movement, a second shift key to move the platen and said support each to the opposite limit of its movement, stops to determine said limits, means to restore the platen and said support to their normal positions of rest when the shift keys are released, an additional shift key operable to shift the platen and said support in the same directions from their normal positions of rest as they are shifted by one of the first-mentioned shift keys, but through less distances, and a stop automatically made effective by the operation of said additional shift key to determine the limit of movement of the platen and said support by said additional key.
33. In a typewriting machine, the combination with a platen and a type-bar support, each shiftable in opposite directions from a normal position of rest, of a connecting means between the platen and said support for causing them to move simultaneously,

- but in opposite directions, a shift key to operate said connecting means and move the platen and support in opposite directions from their normal position of rest, a second shift key for operating said connecting means to move the platen and said support in the reverse directions from those in which they are moved by the first-mentioned shift key, and a centering device for returning 5 said connecting means to normal position when either shift key has been operated, and yieldingly holding said means and the platen and said support in their normal position of rest.
- 10 34. In a typewriting machine, the combination with a platen, of a type-bar support, a rock shaft, rock arms on said shaft and connected respectively to the platen and said support, for shifting the platen and support 15 in opposite directions when the shaft is rocked, shift keys for rocking said shaft in opposite directions and thereby shifting the platen and said support from a normal position of rest to different case positions, a cam 20 secured to said shaft and having oppositely inclined cam faces, and a centering roller, normally engaging said cam faces with a yielding pressure to hold the rock shaft in 25 its normal position of rest, said roller arranged to ride up one cam face when the shaft is rocked in one direction, and to ride up the other cam face when the shaft is rocked in the opposite direction from its normal position of rest, said roller operable 30 automatically to restore said rock shaft to said normal position when the shift keys are released.
35. In a typewriting machine, the combination with a platen and a type-bar support, 40 of type-bars mounted on said support, said platen and support each shiftable up and down from a normal intermediate position of rest to different case positions, connecting means between said support and platen for 45 causing the weight of said support to apply a lifting power to the platen, and for causing the weight of the platen to apply a lifting power to said support, whereby said platen and said support effect a counterbalancing 50 action on each other, shift keys for shifting the platen and said support simultaneously in opposite directions from their normal intermediate position of rest, and means for automatically returning said parts and holding 55 them in their intermediate position of rest.
36. In a typewriting machine, the combination with a platen and a type-bar support, 60 of type-bars mounted on said support, said support shiftable to bring the type-bars to different case positions, and a universal bar frame comprising a pair of mechanically-connected parts, one mounted on said support to shift therewith while the other part 65 remains stationary, the first-named part having 70 a universal bar in the path of the type-bars so as to be actuated by the latter during their type strokes, thereby to move both parts together as a unit with relation to the support in a direction transverse to the direction in which the support is shiftable.
37. In a typewriting machine, the combination with a platen, of a type-bar support, type-bars mounted thereon, means to shift said support up and down to different case 75 positions, a universal bar frame comprising a pair of mechanically-connected parts, one mounted on said support to shift up and down therewith, so that its position relative to the type-bars is unaffected by the shifting of the said support, and comprising a universal bar lying in the path of the type-bars and operated thereby during the type strokes to move said part rearwardly, and the other part being connected to the first part to move therewith as a unit in a forward and rearward direction, said other part having a vertical sliding connection with the first part to permit the latter to shift up and down with said support while said other 80 part remains at rest, and supporting means on which said other part is mounted for forward and rearward movement.
38. In a typewriting machine, the combination of type-bars, four different characters 85 carried by each type-bar, a platen having a normal rest position corresponding with one character, separately-controlled means for shifting the platen in opposite directions from said normal rest position to rest positions corresponding with the other of said characters and maintaining it in said rest positions, a supporting frame in which said type-bars are pivoted, and means to shift 90 said frame simultaneously with the shifting 95 of the platen.
39. In a typewriting machine, the combination of a platen, a system of types, and means for simultaneously shifting the platen and the types from a normal relative position to any one of three different relative 100 printing positions.
40. In a typewriting machine, the combination of a platen, a system of types, means for simultaneously shifting the platen and the types from a normal relative position to any one of three different relative printing positions, and stops to limit the shifting movements of the platen and type system 105 at said printing positions.
41. In a typewriting machine, the combination of a platen, a system of types, and means to shift them simultaneously in opposite directions from normal relative positions to one relative printing position, and 110 in the reverse directions from normal relative positions to two different printing positions.
42. In a typewriting machine, the combination of a platen, a system of types, means 115

for shifting the platen and type system in opposite directions from normal relative positions each to one printing position, means to shift the platen and type system in reverse directions from said normal relative positions each to two different printing positions, and stops to positively limit the shifting movements of the platen and type system at each of said printing positions.

ALFRED G. F. KUROWSKI.
